CLAIM

The ornamental design for a multi tube carrier, as shown and described.

DESCRIPTION

FIG. 1 is a perspective view of a multi tube carrier showing our new design;

FIG. 2 is a front view of the multi tube carrier shown in FIG. 1;

FIG. 3 is a rear view of the multi tube carrier shown in FIG. 1;

FIG. 4 is a right side view of the multi tube carrier shown in FIG. 1;

FIG. 5 is a left side view of the multi tube carrier shown in FIG. 1;

FIG. 6 is a bottom view of the multi tube carrier shown in FIG. 1; and,

FIG. 7 is a top view of the multi tube carrier shown in FIG. 1.

The broken lines in the drawings depict portions of the multi tube carrier that form no part of the claimed design.

1 Claim, 7 Drawing Sheets
